US00D872793S

(12) **United States Design Patent** (10) **Patent No.:** **US D872,793 S**
(45) **Date of Patent:** **** Jan. 14, 2020**

(54) **EYEGLASSES**

(71) Applicant: **Dolby Laboratories Licensing Corporation**, San Francisco, CA (US)

(72) Inventors: **Douglas J. Gorny**, Pacifica, CA (US); **Andrew John Healy**, San Francisco, CA (US); **Thao D. Hovanky**, San Francisco, CA (US); **Barret Lippey**, Foster City, CA (US); **Matthew York Sugarmann**, Redondo Beach, CA (US)

(73) Assignee: **Dolby Laboratories Licensing Corporation**, San Francisco, CA (US)

(**) Term: **15 Years**

(21) Appl. No.: **29/637,318**

(22) Filed: **Feb. 15, 2018**

(51) LOC (12) Cl. **16-06**

(52) U.S. Cl.

USPC **D16/326**

(58) **Field of Classification Search**

USPC D16/300, 313, 314, 326

CPC G02C 3/003

See application file for complete search history.

(57) **CLAIM**

The ornamental design for eyeglasses, as shown and described.

DESCRIPTION

FIG. 1 is a front perspective view of eyeglasses showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate portions of the eyeglasses which form no part of the claimed design.

1 Claim, 6 Drawing Sheets
